UNITED STATES PATENT OFFICE.

LEONARD MYERS, OF GLOVERSVILLE, NEW YORK.

TOY ANIMAL AND METHOD OF MAKING THE SAME.

Application filed January 18, 1922. Serial No. 530,046.

To all whom it may concern:

Be it known that I, LEONARD MYERS, a citizen of the United States, and a resident of Gloversville, in the county of Fulton and State of New York, have invented new and useful Improvements in Toy Animals and Methods of Making the Same, of which the following is a full, clear, and exact description.

10 This invention relates to improvements in toy animals and methods of manufacturing the same, an object of the invention being to provide a toy animal formed of sheep-skin, llama-skin, or other animal skin, which will be very attractive and lifelike in appearance, and will prove an interesting and amusing plaything for children.

15 A further object is to provide a device of this character so constructed that it may be washed with soap and water without injuring the same.

20 Another object of the invention is to provide a novel method of manufacturing the toys so that they will be exceedingly strong and durable in use, and capable of withstanding a great deal of rough handling without breaking, tearing, or being pulled out of shape.

25 With these and other objects in view, the invention consists in certain novel features of construction and combinations and arrangements of parts as will be more fully hereinafter described and pointed out in the claim.

30 35 In the accompanying drawings:

Figure 1 is a perspective view of the toy;

Figure 2 is a perspective view of several sections of the skin from which the toy is made, showing half of the skin ready for stuffing and ready for attachment to the other half; one of the legs of the toy is shown turned inside out in this figure;

Figure 3 is a sectional view through the lower end of a leg of the completed toy; and

40 45 Figure 4 is a perspective view of one of the eyes of the toy.

Referring in detail to the drawings, my improved toy is formed of a number of pieces of sheepskin or similar material designated by the reference numeral 2. These pieces are sewed together on the leather side, the skin having been previously cut in accordance with any desired pattern to give the desired shape. I have shown in the drawings a toy bear, and in Figure 2, I have shown one half of the skin which forms the

toy with the head portion attached thereto ready for stuffing and attachment to the remaining half of the toy.

It will be noted that the stitching 3 which connects the various pieces of skin is located on the leather side so that no seams appear on the woolly outside of the toy. The lower ends of the hollow legs 4 are closed by sewing pieces of suitably treated leather 5 therein which constitute the soles of the foot portions of the legs. The leather 5 represents the feet of the animal. Small pieces of skin 6 sewed to the head represent the ears and these pieces are attached to the head 7 in such a manner that the leather side 7 is exposed, representing the inside of the animal's ears and giving a more lifelike appearance to the toy.

70 75 Representations of the nose 8 and mouth 9 are made by sewing dark colored threads on the head of the toy after the same has been stuffed. The eyes 10 are attached in a unique manner to prevent their being pulled out. Each of the eyes is attached to a length 80 of wire 11, which pierces the head of the animal and is twisted inside of the head, as indicated at 12 to effectively prevent the eyes from being pulled out. The lifelike appearance of the toy is further enhanced by the 85 provision of a number of spaced stitches 13 of dark colored thread at the forward ends of the leather feet 5, these stitches serving to represent the claws of the bear. A collar 14 may be provided, or the animal may be otherwise decorated to suit the trade. The animal is stuffed with sterilized goat's hair, indicated at 15. This stuffing used in connection with the genuine sheepskin permits the 90 95 toy to be washed with soap and water without damaging the same in any manner. The leather lined feet and ears, the particular manner of attaching the eyes and the way in which the representations of the nose, mouth and claws are formed, all cooperate 100 to provide a toy which is practically indestructible.

As hereinbefore suggested, I have also invented a new method of forming the toys. By my improved method the various sections 105 of the skin are cut in accordance with a suitable pattern and the sections are sewed together on the leather side, the two halves of the bear being formed in this manner. The legs of the toy are then turned inside out and the sections are partially joined together, 110 leaving a sufficient opening for the entrance

of the stuffing material, which is preferably the goat's hair, as above mentioned. After the stuffing operation has been completed, the sewing together of the sections is also 5 completed, the claws, nose and mouth are sewed on, and the collar attached to conceal the external lines of stitching around the neck of the animal. It will of course be understood that the leather feet are sewed in 10 and the eyes attached before the skin is turned inside out for stuffing.

It will of course be evident that other animal skin, beside sheepskin and llama skin might be used and that the toys might be 15 constructed in various shapes to represent animals other than bears.

Although I have illustrated one of the preferred embodiments of my invention, it will be apparent that various slight changes 20 and alterations might be made in the general form and arrangement of the parts described without departing from the invention, and hence I do not wish to limit myself to the precise details set forth, but shall consider

myself at liberty to make such slight changes 25 and alterations as fairly fall within the spirit and scope of the appended claim.

I claim:

As a new article of manufacture a toy bear formed of pieces of animal skin sewed 30 together with the woolly side out to form the head, body and legs and the whole stuffed, pieces of leather secured to the lower ends of the legs to extend below the same and form therewith feet, the forward ends of the 35 feet being provided with spaced stitches to represent claws, ears formed of pieces of similar skin sewed to the head with the woolly side out and exposing the leather side to represent the inside of the ears, eyes each 40 carried by a wire extending into the inside of the head and twisted with the twisted portion resting against the inside of the head, and threads contrasting in color to the color of the wool of the skin and sewed 45 onto the head to represent the nose and mouth.

LEONARD MYERS.
